APPARATUS FOR PUNCHING SLAT ASSEMBLIES
Alfred Charles Taylor, Clayfield, Brisbane, Queensland, Australia, assignor to Hunter Douglas International (Quebec) Ltd., Montreal, Quebec, Canada

Filed Oct. 25, 1961, Ser. No. 147,621

Claims priority, application Australia, Oct. 28, 1960,
66,069

6 Claims. (Cl. 153—10)

This invention relates to apparatus for punching slat assemblies, and it has more particular reference to apparatus for punching the rolled-edge joints of certain types of slat assemblies which are usable for awnings, screens, blinds, doors or the like.

It is well-known to provide an awning or the like in which a number of narrow metal slats are joined side by side in parallel relationship, each slat having each longitudinal edge rolled for hooked engagement with an oppositely-rolled edge of the slat immediately adjacent on either side to form hinged connections. To prevent adjacent slats from sliding longitudinally relative to one another, it is customary to punch each joint on the inner face of the assembly near to each end thereof, this operation having been done to date by manual punching or pinching of each individual joint. It will therefore be appreciated that considerable time, care and effort have been required for this purpose up to the present time, with resultantly high operational costs.

The present invention has been devised to simplify the procedure in punching slat joints of this type, and it accordingly has for its principal object the provision of apparatus of relatively simple and inexpensive construction which may be used with ease by even an unskilled operator to achieve rapid and accurate punching.

Another object of the invention is to provide apparatus of the aforementioned type for punching slat joints, such apparatus lending itself to semi-automatic operation in a most reliable and efficient manner. Other objects and advantages of the invention will be hereinafter apparent.

With the foregoing and other objects in view, the invention resides broadly in apparatus for punching rolled-edge joints of slot assemblies, including a punch-mounting frame adapted to be moved transversely across the slot assembly and having an engagement member adapted to engage contact portions of the slats; a punch mounted on the frame and adapted to occupy a punching position adjacent a slot joint when the engagement member is engaged with a contact portion of a slot, and means for actuating the punch when it is in a punching position so that the adjacent slot joint will be punched. Other features of the invention will become apparent from the following description.

In order that the invention may be more readily understood and put into practical effect, reference will now be made to the accompanying drawings, wherein:

FIG. 1 is a perspective view of one end of a table having fitted thereon slat-punching apparatus in accordance with the invention, the table being shown partly broken away;

FIG. 2 is a plan view, also broken away, of the table, slat assembly and slat-punching apparatus shown in FIG. 1;

FIG. 3 is a perspective view of the inner side of the slat-punching apparatus, with the punch thereof in inoperative attitude, and

FIG. 4 is a broken-away, outer side elevation of the

2

slat-punching apparatus, showing the punch in operative attitude.

Referring initially to FIGS. 1 and 2 of the drawings, there is shown one end of a flat, rectangular table 10 mounted on legs 11 and supporting a slat assembly 12 of which the slat joints are to be punched. The end of the table 10 which is shown is provided with slat-punching apparatus, as illustrated, while it is to be understood that the other end of the table which is not shown also has thereon slat-punching apparatus which is of identical but oppositely-arranged construction.

The slat assembly 12 is of normal rectangular shape, being made up of a series of parallel narrow metal slats 13 of arcuate cross-section, each of which has its longitudinal edges oppositely rolled, each edge of a slat 13 being engaged hingedly with an oppositely-rolled edge of an adjacent slat to form a joint 14. As shown in FIG. 4, each slat 13 has one edge 15 simply rolled in the direction of curvature of the body of the slat, but the other edge 16 is oppositely rolled adjacent a longitudinal shoulder of the slat, with the result that the joints 14 protrude on that side of the assembly 12 on which the slats 13 have their centres of curvature. This is the "inner" side of the assembly, whereas the other or "outer" side of the assembly is that which is normally arranged to face upwards in an assembled awning. As previously mentioned, the joints 14 are to be punched on their inner faces, and the assembly 12 is therefore disposed on the table 10 so that the inner side thereof faces upwards, the protruding joints 14 then also facing upwards.

At the end or transverse edge of the table 10, there is fixedly mounted an edge-mounting strip 17 lying flat along the edge of the table and extending inwards for a short distance, while a vertical edge-retaining bar 18 is secured outwardly thereof so that the end of the slat assembly 12 may lie on the strip 17 with the ends of the slats 13 retained on the table and aligned by the edge-retaining bar 18. Each end of the edge-mounting strip 17 extends beyond the table 10 and has secured thereto at right angles a horizontal, longitudinal and outwardly-extending supporting bar 19 having at its outer end a mounting block 20 for a transverse guide rod 21 arranged parallel to the edge-mounting strip 17 but spaced outwardly thereof and at a slightly higher level. It is to be understood that the word "longitudinal" is used herein relative to the direction of the length of the table 10 and slats 13, while "transverse" has reference to the direction at right angles to or across the table 10 and slats 13.

Mounted for sliding movement along the guide rod 21 is a punch-mounting frame, indicated generally by the numeral 22. For this purpose, there is provided a pivot sleeve 23 closely slidable along the guide rod 21 and pivotable thereabout, the sleeve 23 also passing through and welded to an upstanding longitudinal frame arm 24 which extends over the edge-mounting strip 17 but may be raised above the strip 17 and moved pivotally clear thereof outwardly of the end of the table 10 by pivoting the sleeve 23 about the guide rod 21. In this regard, an upward extension plate 25 of the frame arm 24 is provided at one side, hereinafter referred to as the "front" side, with a weighted block 26 adapted to hold the frame arm 24 normally over the strip 17, but a pivot-control rod 27 extends upwards from the block 26 and has an upper knob 28 so that the punch-mounting frame 22 may be pivoted as aforementioned about the guide rod 21. At the same time, a draw-control rod 29 extends forwards from the frame arm 24 and has a front hand knob 30 whereby

the frame arm 24 and punch-mounting frame 22 may be drawn backwards or forwards transversely with sliding movement of the pivot sleeve 23 along the guide rod 21.

Secured to the rear face of the extension plate 25 and extending rearwards thereof is a mounting bracket 31 for a solenoid 32, the latter being supported thereon with its core 33 arranged in vertically slidable manner. The upper end 34 of the solenoid core 33 extends freely above the housing for the coil of the solenoid 32, while the lower end 35 of the solenoid core 33 passes through an aperture in the solenoid mounting bracket 31 and is therefore free to move reciprocably past and parallel to the frame arm 24 directly above the edge-mounting strip 17. A bar 36 through the lower end 35 of the solenoid core 33 has at each end a light tension spring 37 extending vertically upwards and connected to a respective upper mounting hook 38 secured to a top plate 39 of the coil housing of the solenoid 32. Thus, the solenoid core 33 will normally be maintained in the uppermost position shown in FIG. 3 by the action of the springs 37 except when the solenoid 32 is actuated as hereinafter described.

To the rear face of the frame arm 24 directly beneath the solenoid core 33, there is secured a punch-mounting block 40 having therethrough a vertical, round-section aperture 41 coaxial with the solenoid core 33, this aperture 41 slidably housing a rod-like, plunger-type punch 42 provided at its lower extremity with a coaxial, tapered punch-tip 43 for performing the required punching operations on a slat joint 14. The upper end of the punch 42 extends above the top of the punch-mounting block 40 so that its upper extremity may be struck by the descending solenoid core 33, and it has fixed to its upper end a yoke member 44 disposed at an angle to the punch-mounting block 40, as illustrated.

The front end of the yoke member 44 has a vertical aperture 45 slidably accommodating a guide pin 46 secured to and extending upwards from the punch-mounting block 40, a compression spring 47 about the pin 46 and between the yoke 44 and block 40 acting normally to maintain the yoke 44 in uppermost position in which its rear portion engages under a washer 48 mounted adjustably as to height on a limiting pin 49 of the block 40. The rear extremity of the yoke 44 is vertically bored and tapped to accommodate screw-threadedly an adjustable clearance screw 50 disposed clear of the inner side of the punch-mounting block 40 by virtue of the angular disposition of the yoke 44 as previously mentioned.

On the inner side of the punch-mounting block 40, there is a horizontal pivot pin 51 providing a pivot axis for a trip-mounting block 52 arranged parallel to the block 40 and adapted to be moved pivotally in a transverse plane. The lower section of the trip-mounting block 52 beneath the pivot pin 51 has a lengthwise bore housing a slideable trip rod 53 which extends from each end thereof, and the front end of the trip rod 53 has fixed thereto an upwardly extending guide and stabilising lug 54 having an aperture through which may pass slidably a guide pin 55 secured to the front of the block 52 and extending forwards parallel to the rod 53. The rear end of the trip rod 53 passes closely and slidably through an aperture in a spring-loaded manner of a spring-mounting plate 56 secured removably by screws to the rear end of the trip-mounting block 52, the rear lower section of the block 52 being cut away, as illustrated, so that the exposed trip rod 53 may have an encircling compression spring 57 bearing at its rear end on the spring-mounting plate 56, while its front end is secured by a pin 58 to the trip rod 53. In this way, the trip rod 53 will normally be urged in a forward direction to a foremost position in which the guide and stabilising lug 54 is spaced in front of the front end of the trip-mounting block 52.

The pivot pin 51 is disposed towards the front end of the trip-mounting block 52, and a front tension spring 59 connects the upper front portion of the block 52 to a forward position on the punch-mounting block 40. By virtue

of the spring 59, the rear end of the trip-mounting block 52 will normally be in a raised attitude, while the front end of the trip rod 53 will be in its lowermost attitude, the trip-mounting block 52 being urged by the spring 59 against a limiting stop lug 60 on the punch-mounting block 40. The adjustable clearance screw 50 of the yoke member 44 will be located in a recess 61 in the upper surface of the trip-mounting block 52 in rear of the pivot axis 51.

10 The punch-mounting block 40 also has at its rear end a mounting plate 62 for a microswitch 63 arranged with its contact button 64 adjacent the rear end of the trip rod 53 and in line therewith when the latter is in its aforementioned normal attitude in which the front end is lowermost. Standard electrical connections extend from the microswitch 63 through a lead 65 to the contacts of the solenoid 32 in a contact box 66, the latter also having standard electrical connections (not shown) to a supply of mains electricity. Thus, depression of the contact button 64 of the microswitch 63 will cause the solenoid 32 to be actuated to move its core 33 downwards against the punch 42, while release of the button 64 will de-energise the solenoid 32, and the core 33 will be returned to uppermost position by the springs 37. The microswitch 63 may be mounted adjustably by means of screws in slotted holes in the plate 62 so that its location and that of the button 64 relative to the rear end of the trip rod 53 may be adjustably varied.

30 The free inner end of the frame arm 24 is provided with a slide shoe 67 secured adjustably as to height by means of bolts in slotted holes through the frame arm 24 and an upward shoe-mounting arm 68. The slide shoe 67 has a non-abrasive lower contact surface adapted to ride across the slat joints 14 so that the latter may support the punch-mounting frame 22 during sliding movement. At the same time, at the front of the frame arm 24 directly above the edge-retaining bar 18, there is a roller 69 adapted to engage upon the top surface of the bar 18 to take the weight of the frame 22 when there is no slat assembly on the table, and also adapted to ride up and along a ramp 70 at the rear end of the edge-retaining bar 18 so that the trip rod 53 will be carried across and above the rearmost edge of the slat assembly 12 without engaging same.

35 To commence operation, the slat assembly 12 is laid on the table 10 with its inner face uppermost, each slat 13 having its plain rolled edge 15 towards the front of the table, and the other rolled edge 16 (adjacent the slat shoulder) at the rear, the ends of the slats being aligned against the edge-retaining bar 18. The rear edge of the 40 rearmost slat is then hooked over a fixed hook strip 71 secured to the edge mounting strip 17, while at spaced positions along the rear edge of the table 10, the slat edge is similarly engaged with adjustably-positioned hook strips 72.

45 On the other hand, to grip the front edge of the foremost slat or any other slat in front of the machine, the guide rod 21 has a loose sleeve 73 with a catch bar 74 and knob 75, a hook 76 thereof being engaged over and into the rolled slat edge. By pulling the knob 75 forwards, the catch bar 74 may be drawn forwards to stretch 50 the slat assembly to desired tautness of the joints, and when the bar 74 is then released, it will remain in this stretched position because the sleeve 73 is arranged to have a lever-type, frictional catch action on the guide rod 21.

55 If the punch-mounting frame 22 is initially taken to its 55 rearmost position, the roller 69 will ride on the ramp 70 and will support the frame with the slide shoe 67 and trip rod 53 above the slat assembly. The punch-mounting frame 22 may then be drawn forwards by the hand 60 knob 30 of the draw-control rod 29 until the trip rod 53 and punch 42 pass the first or rearmost edge, whereupon the roller 69 will have moved off the ramp 70, and the slide shoe 67 will be in contact with the slat joints. The 65 front end of the trip rod 53 will then be down against

the slat and will come in contact with the first protruding joint 14, this being the initial or "contact" attitude of the trip rod 53, the punch 42 then being slightly in rear of the same joint 14. Further forward movement of the knob 30 will cause the trip rod 53 to be depressed rearwards until it reaches an "engaged" attitude at which it depresses the contact button 64 of the microswitch 63, and at which also the punch 42 will be directly over the slat joint in a "punching" position. Thus, if the power is on, the solenoid 32 will be actuated to move the core 33 downwards to strike the punch 42 so that the punch-tip 43 will strike and punch the two adjacent uppermost sheet metal rolled portions of the two slat edges constituting the joint 14.

As the punch 42 moves downwards, the attached yoke 44 and clearance screw 50 also move down so that the clearance screw 50 will strike the trip-mounting block 52 and cause its rear end to move down and its front end up as it pivots about the pivot pin 51. Thus, the front end of the trip rod 53 will be raised clear of the joint 14, whereupon the spring 57 will return it forwards to a position ahead of the joint, as shown in FIG. 4, while the rear end of the trip rod 53 will move clear of the microswitch button 64, so that the solenoid 32 will be de-energised and the core 33 will return to uppermost position.

The punch 42 and yoke 44 will thus also return to uppermost position by virtue of the spring 47, whereupon the clearance screw 50 will also be uppermost, and the spring 59 may return the trip-mounting block 52 to engage the stop lug 60. The trip rod 53 will then be again in line with the contact button 64, with its front end lowermost ready for contact with the next joint. This sequence of operations will be repeated as the apparatus is drawn forwards across the slats of the slat assembly, each joint being punched as the trip rod 53 comes to engaged attitude. As the punch-tip 43 is located at a short distance from the edge-retaining bar 18, the series of punched depressions or perforations in the slat joints will lie in a straight line which is spaced from and parallel to the edges of the slats. The slat assembly 12 may then have the opposite ends of the slats punched in the same manner by the identical but oppositely-arranged apparatus at that end of the table, the direction of movement of the apparatus for the punching operations being the same.

If desired, slat assemblies punched in this manner may also be provided with locking rivets of the type described in our Australian patent application No. 44,244/58, so that a double locking action will be achieved, and also added attractiveness will be given to the ends of the joints.

While apparatus as described and illustrated will therefore be found very effective in achieving the objects for which the invention has been devised, it will of course be understood that this particular exemplary embodiment of the invention is illustrative only and may be subject to many modifications of constructional detail and design. The invention will be understood to embrace all modifications and variations as lie within its scope and ambit, as defined by the appended claims.

What I claim is:

1. Apparatus for punching rolled-edge joints of slat assemblies, including a table adapted to support a slat assembly, said table being provided with an edge-retaining bar and an edge-retaining means in parallelism across the table and adapted to retain the slats thereon with their ends in alignment; a guide rod, a punch-mounting frame mounted for sliding movement across the table on the guide rod in such manner that the frame may be moved transversely across the slats at or near to the end of the assembly; an engagement member associated with the frame and adapted to engage successive contact portions of the slats; a punch mounted on the frame above the slats and adapted to be moved downwards on to the latter, the punch occupying a punching position above a slat

joint when the engagement member is engaged with a contact portion of a slat; and means for actuating the punch when it is in a punching position to cause it to move downwards to punch the slat joint therebeneath.

5 2. Apparatus for punching rolled-edge joints of slat assemblies according to claim 1, wherein the guide rod is spaced from the punch of the punch-mounting frame, the latter having a pivot sleeve fitted slidably and pivotally on the guide rod so that the frame may be moved slidably along the guide rod or pivotally raised about the axis of the guide rod and sleeve to raise the punch clear of the slat assembly, said punch-mounting frame being provided with a slide shoe adjacent the punch and adapted to bear slidably against the slat assembly when the frame is moved slidably in its pivotally lowered attitude.

10 3. Apparatus for punching rolled-edge joints of slat assemblies according to claim 1, wherein there are provided means for securing the slat assembly on the table in a stretched condition, said means comprising fixed hook members at one side of the table adapted to be engaged with the free rolled edge of the end slat of the assembly at that side, and adjustable hook means at the other side of the table adapted to be engaged with a slat on that side and to be secured in a desired position to tension the assembly, said adjustable hook means being mounted for sliding movement on the guide rod.

15 4. Apparatus for punching rolled-edge joints of slat assemblies, including a table adapted to support a slat assembly, said table being provided with an edge-retaining bar and edge-retaining means in parallelism across the table and adapted to retain the slats thereon with their ends in alignment; a guide rod, a punch-mounting frame mounted for sliding movement across the table on the guide rod in such manner that the frame may be moved transversely across the slats at or near to the end of the assembly; an engagement member associated with the frame and adapted to engage successive contact portions of the slats; a punch mounted on the frame above the slats and adapted to be moved downwards on to the latter, the punch occupying a punching position above a slat joint when the engagement member is engaged with a contact portion of a slat; and means for actuating the punch when it is in a punching position to cause it to move downwards to punch the slat joint therebeneath, the guide rod being spaced from the punch of the punch-mounting frame, the latter having a pivot sleeve fitted slidably and pivotally on the guide rod so that the frame may be moved slidably along the guide rod or pivotally raised about the axis of the guide rod and sleeve to raise the punch clear of the slat assembly, said punch-mounting frame being provided with a slide shoe adjacent the punch and adapted to bear slidably against the slat assembly when the frame is moved slidably in its pivotally lowered attitude; wherein the means for actuating the punch includes a punch-actuating member consisting of a solenoid device having its core arranged to strike the punch to move it against the slat joint when the punch is in a punching position and connector means comprising electrical switch means associated with the engagement member and electrically connected to the solenoid, the switch means acting to actuate the solenoid to operate the punch each time the engagement member is engaged with a contact portion of a slat; the engagement member being a trip member normally urged towards the slat assembly.

20 5. Apparatus for punching rolled-edge joints of slat assemblies according to claim 4, wherein the trip member is pivotally mounted and also spring-loaded for sliding movement relative to the frame and punch between an initial contact position in which it may make contact with a slat joint and an engaged position in which the punch is in its punching position, operation of the punch when it is in this position acting to clear the trip member pivotally from the slat joint in a direction away from the slat assembly and joints so that the trip member may return

25 60 55 65 70 75

slidably under the action of its spring-loading to its initial position ready for contact with another slat joint.

6. Apparatus for punching rolled-edge joints of slat assemblies according to claim 4, wherein the trip member is spaced from the switch means in its initial position but will move slidably into contact therewith in its said engaged position so that the solenoid will be actuated to operate the punch, the latter then acting to clear the trip member pivotally from the switch means to de-energize the solenoid.
